UNITED STATES PATENT OFFICE.

JOSEPH W. DROLL, OF OAKLAND, CALIFORNIA.

MATTRESS-ROLL-FORMING MACHINE.

1,300,139.

Specification of Letters Patent.

Patented Apr. 8, 1919.

Application filed March 15, 1917. Serial No. 156,467.

To all whom it may concern:

Be it known that I, JOSEPH W. DROLL, a citizen of the United States, residing in the city of Oakland, in the county of Alameda and State of California, have invented a new and useful Improvement in Mattress-Roll-Forming Machines, of which the following is a specification.

My invention relates to roll forming machines for mattresses and the like wherein a pair of roll forming fingers operate in conjunction with sewing means to secure the roll when formed; and the objects of my invention are—

15 First, to provide an improved roll forming machine for mattresses and the like;

Second, to provide improved means for temporarily retaining the formed roll;

20 Third, to provide improved means for permanently securing the formed roll;

Fourth, to provide improved means to enter a mattress and draw the stuffing or filling thereof firmly against the sides or ticking thereof while the roll is being formed;

25 Fifth, to provide means for moving the roll securing means forward while the roll forming means are in operation;

Sixth, to provide improved means for forming and securing a roll on the corner 30 of a mattress that may be adjusted relatively to the said mattress; and

Seventh, to provide improved means for moving the entire machine around the edge or periphery of a mattress to form and secure rolls thereon.

I accomplish these several objects by means of the preferred form of the device disclosed in the drawings forming a part of the present specification, wherein like characters of reference are used to designate similar parts throughout the said specification and drawings, and in which—

Figure 1 is a vertical sectional view of a table disclosing a mattress in section thereon 45 and the roll forming machine applied to the table and engaging the mattress, the roller handles being removed.

Fig. 2 is a broken side elevation of Fig. 1.

Fig. 3 is an enlarged front elevation of 50 the roll forming and securing means shown in vertical position with the roll retaining means engaging and the roll forming means disengaging the mattress.

Fig. 4 is a view similar to Fig. 3 but dis-

closing the roll forming means in operative 55 position and the roll securing or sewing means withdrawn from the mattress.

Fig. 5 is a broken side elevation on an enlarged scale of the left hand side of Fig. 4 disclosing the sewing shuttle and the roll 60 forming means disengaged.

Fig. 6 is a view similar to Fig. 5 but on a smaller scale disclosing the parts in another position.

Fig. 7 is a broken plan view of the mechanism for moving the machine forward at 65 regular intervals.

Fig. 8 is a broken plan view of one corner of the mattress supporting table disclosing the manner in which the machine travels 70 around the corners of said table; and

Fig. 9 is a broken plan view of the table disclosing the arrangement of the supporting rails.

Referring to the drawings, the numeral 1 75 is used to designate a suitable table having side-boards 2 thereon upon which are mounted a supporting rail 3 and a rack 4. A guide channel 6 is mounted on the under side of the table 1 and near the edge thereof. 80

A suitable supporting frame 7 is provided with a pair of supporting rollers 8 which rest and ride upon the rail 3. A guide roller 9 engages the guide channel 6 to align the machine with the work in a manner 85 hereinafter more fully described.

To further support the supporting frame 7 I have provided a roller 11 on each side of said frame 7 and connected thereto by a pivotally mounted bracket 12. 90

A suitable motor 14 is mounted upon a shelf or horizontal extension 16 of the frame 7 and the motor shaft 17 is provided with a worm 18 meshing with and driving a worm gear 19 on a vertically disposed shaft 21 rotatably mounted within the frame 7.

The shaft 21 is provided with a cam 22 to operate a lever 23 pivotally mounted upon the frame 7. One end of the lever 23 extends through an aperture 24 in the frame 7 100 and is provided with a pawl 26 which is arranged to engage the rack 4 on the side board 2 of the table 1 whereby the frame 7 may be moved forward equal distances at regular intervals, the purpose of which will 105 hereinafter be more fully set forth.

The frame 7 is also provided with a sector 28 having slots or grooves 29 therein to

engage and retain a lever 30 secured to a super-frame 31 whereby the angle of the frame 31 may be altered relatively to the position of the frame 7 and table 1.

- 5 A bevel gear 32 is rotatably mounted upon the frame 31 and is connected with the drive shaft 21 of the frame 7 by means of a suitable universal joint 33. The bevel gear 32 meshes with and drives a second bevel gear 34 rigidly secured to a surface cam 36 rotatably mounted within the super-frame 31 to operate a lever 37 pivotally mounted to the upper end of the frame 31 as at 38. The lever 37 carries on the lower end thereof of an arcuate needle 39 which forms the sewing mechanism in conjunction with a shuttle 41 secured to the lower end of a lever or arm 42 which is operated by means of a face cam 43 secured to the surface cam 36.

Slidably mounted upon a square rod 46, secured to the frame 31, is a T-head 47 having pivotally mounted therein the roll forming mechanism comprising a pair of arcuate arms 48 terminating in needle fingers 49 which are arranged to enter the top and sides adjacent the corners of a mattress 52 and force the stuffing 53 adjacent the corner into a roll 54, as disclosed in Figs. 1, 3 and 30 4 of the drawings.

The T-head 47 is provided with an upwardly extending rod or standard 56 whose upper end is slidably engaged by a groove or slot 57 in a strut 58 formed integral with the frame 31.

A sleeve 61 is slidably mounted upon the standard 56 and is connected by means of suitable links 62 to the arcuate arms 48. A spring 63 is interposed between the sleeve 61 and the T-head 47 to normally raise the sleeve 61 and withdraw the roll forming mechanism from the mattress 52 as disclosed in Fig. 3 of the drawings.

The sleeve 61 is also provided with a pin 45 66 which is operatively engaged by a cam 67 on the lower end of an arm 68 rigidly secured to the sewing needle arm or lever 37 by means of a counter-shaft 69 pivotally mounted within the top of the frame 31 as at 38.

Roll retaining means are provided in the form of suitable rollers 71 rotatably mounted upon the ends of rods 72 pivotally mounted upon a bar or head 73 secured to the square rod 46 in advance of the roll forming arms 48, said rods terminating in suitable handles 76 by means of which the said rods 72 may be partially rotated on their pivotal points against the tension of springs 74 to separate the rollers 71 to release or disengage same from the mattress 52.

An arcuate guide frame 77 is rigidly secured to the lower end of the frame 31 and 65 is arranged to partially surround the formed

roll 54 as disclosed in Fig. 3 of the drawings. The guide frame 77 is provided with an aperture 78 through which thread is drawn by the needle 39 from a suitable spool or drum 81, to form a loop to be engaged by the shuttle 41 to form what is commonly known as the lock-stitch to permanently secure the formed roll 54.

The retaining rolls 71 are provided on the periphery thereof with needles 82 to effectively engage and retain the ticking of the mattress 52 and thereby effectively retain the formed roll 54.

The T-head 47 is slidably mounted upon the square rod 46 so that the arms 48 may 80 retain their engagement with the formed roll 54 while the machine or frame 31 carrying the sewing mechanism is moved forward to make the next stitch. The pin 66 is slightly shorter than the distance of the 85 forward movement so that when said forward movement is completed the pin 66 has become disengaged from the cam 67 and the spring 63 is then free to move the sleeve 61 upward to disengage the roll forming 90 means or arms 48 and needles 49 thereon from the roll 54.

A spring 84 is mounted upon the square rod 46 and interposed between the guide 77 and the T-head 47 and arranged to move 95 the said T-head and roll forming means mounted thereon, forward. But when the needle 39 is withdrawn from the roll 54 the cam 67 will be in the position disclosed in full lines in Fig. 4 of the drawings and the spring 84 will move the T-head 47, the sleeve 61 and pin 66 forward until the end of said pin 66 engages or abuts against the back face of the cam 67 as disclosed in Fig. 5 of the drawings, and in dotted lines in 100 Fig. 4 of the drawings.

In order to assist in forming the loop made by the needle 39 I have provided an arcuate channel 87 as disclosed in Fig. 3 of the drawings. This arcuate channel 87 lies under the path of the needle 39 and frictionally engages the thread on the under side of the needle 39 to frictionally engage the under thread when the needle 39 is withdrawn. This frictional engagement will 115 cause the loop to be formed on the upper side of the needle 39 and in front of the shuttle 41 as disclosed in dotted lines in Fig. 3 of the drawings.

The next forward movement of the lever 42 will pass said shuttle 41 through the loop as the said shuttle 41 is frictionally held in position by means of spring retainers 88, the threaded loop passing between said shuttle 41 and the said retainers 88 as said shuttle moves forward.

As the needle 39 is fully withdrawn the loop formed engages the thread from the shuttle 41 and forms the well known lock stitch.

The function of the machine is to operate the roll forming means to engage the mattress 52 and form a roll thereon and to retain said roll forming means in engagement with the mattress while the entire frame 31 moves forward or toward said roll forming means and stitches the roll so formed, and then releases the roll forming mechanism and moves the same forward to reengage the mattress and form a continuation of the roll.

The operation is as follows:

In starting, the needle 39 is withdrawn as disclosed in Fig. 4 and the roll forming fingers or needles are in the position disclosed in dotted lines in Fig. 4 of the drawings.

The position of the frame 31, and also the roll forming and sewing means thereon, is adjusted relatively to the frame 7 and mattress 52 by means of the lever 30.

The mattress 52 is then adjusted relatively to the roll forming means so that the needles 49 will penetrate the ticking during their descent.

The roll retaining rolls 71 are moved outward against the tension of the springs 74 by means of the handles 76 and then released to permit the needles to engage the ticking and partially form a roll.

By means of the pin 66 the roll forming fingers or arms 48 and needles 49 connected thereto are operated to enter the mattress 52, engage and gather the stuffing 53 and form the same into a roll 54 as disclosed in Figs. 1 and 4 of the drawings.

By starting the motor the cam 22 on the drive shaft 21 operates the lever 23 and pawl 26 pivotally mounted thereon to engage the rack 4 and thereby move the machine and sewing mechanism forward toward the roll forming means, said means, being slidably mounted, meanwhile retaining engagement with the mattress.

The continued rotation of the drive shaft 21 will rotate the cam 36 and cause the needle 39 to penetrate the mattress and operating in conjunction with the shuttle 41 form a lock stitch to permanently secure the formed roll.

As the needle 39 is withdrawn from the formed roll 54 the cam 67 engages the pin 66 and depresses the sleeve 61 thereby operating the roll forming arms 48 and needles 49 to again enter the mattress 52 and form a roll in advance of the last formed roll. As the needle 39 is entirely withdrawn the cam 22 on the shaft 21 operates to move the machine and sewing mechanism forward toward the roll forming means while said means is retaining its engaging relation with the mattress.

When the cam 67 leaves or releases the pin 66 the spring 63 disengages the roll forming means from the mattress and the spring

84 moves said roll forming means forward with the front or free end of the pin 66 against or abutting the back face of the cam 67 until said cam is moved to the position shown in Fig. 3 of the drawings when the spring 84 will complete the movement and again move the pin 66 under the face of said cam 67.

The above process is repeated, the roll forming means engaging the mattress to form the roll and sliding upon the square rod 46 while the machine and sewing means move forward to secure by stitching the formed roll, the retaining rolls 71 meanwhile temporarily retaining the formed roll, until a roll is formed permanently along the entire side of the mattress.

In Figs. 8 and 9 I have illustrated the arrangement of the supporting rails 3 and guide channels 6 whereby the machine may traverse the entire periphery of the table 1 and the mattress 52 thereon thereby forming a continuous roll around the entire periphery of said mattress without disengaging the machine from the mattress or interrupting the stitching.

As the frame 7 travels around the curved corner of the table 1 the roll forming means are held to the working line or center of the roll to be formed by means of a roller 9 rotatably mounted upon the frame 7 and engaging the channel 6.

The rollers 11 pivotally mounted to the frame 7 by means of the arms or levers 12 serve to retain the frame 7 in an upright position while said frame is traveling either around corners of the table or along the straight sides thereof.

When the roll has been formed completely around the edge or upper corner of the mattress 52 the machine is moved slightly forward to withdraw the needle 39 and also cause the cam 67 to release the pin 66.

By pressing the handles 76 together against the tension of the spring 74 the retaining rollers will be disengaged from the mattress and by breaking the threads from the shuttle 41 and needle 39, the mattress may be disconnected from the machine and turned over to repeat the process by forming a roll on the opposite corner thereof.

It is obvious from the foregoing that I have provided an improved mattress forming machine adapted to form a roll on the edge of the mattress or the like, temporarily retaining the formed roll by means of the retaining rolls 71 and to secure permanently the roll so formed and retained, by means of the sewing mechanism.

The details of construction are so susceptible to variation that I do not wish to confine myself to the precise construction shown herein but rather to avail myself of any modifications that may fall properly within the scope of my invention.

Having thus described my invention what I claim as new and desire to secure by Letters Patent is—

1. A mattress roll forming machine comprising a roll forming means to form a roll on the corners of a mattress or the like; suitable retaining rollers arranged to follow the roll forming means and temporarily retain the formed roll; a suitable stitching 70
75
10 needle to penetrate the roll at its junction with the mattress; means for withdrawing the needle and operating the roll forming means simultaneously; and means for moving the needle and retaining rollers forward 15 the length of one stitch while the roll forming means are engaging the roll.
2. A mattress roll forming machine comprising a pair of roll forming fingers to penetrate the top and sides of a mattress adjacent the corner thereof and form a roll on said corner; a pair of retaining rollers to temporarily retain the formed roll; a suitable sewing mechanism to stitch the roll at its junction with the mattress; means for withdrawing the stitching mechanism and operating the roll forming fingers simultaneously; and means for moving the sewing mechanism the length of one stitch after 25
30
35
40
45
50
55
60
65 each stitch is made.
3. A mattress roll forming machine comprising a suitable frame; roll forming means slidably mounted within the frame to form a roll on the corners of a mattress or the like; means for temporarily retaining the formed roll; suitable sewing mechanism to sew the sides and top of the mattress together at the junction of the roll with the mattress; means for moving the sewing mechanism forward a distance equal to the length of one stitch while the roll forming mechanism is engaging the mattress; and means for releasing and moving the roll forming fingers forward during the operation of the sewing mechanism.
4. A mattress roll forming machine comprising a suitable frame; a pair of roll forming fingers pivotally and slidably mounted upon the frame; means for temporarily retaining the roll; stitching mechanism to follow the retaining means and stitch the roll at its junction with the mattress; means for moving the stitching mechanism forward the length of one stitch while the fingers are engaging the roll; and means for releasing the roll retaining means from the mattress.
5. A mattress roll forming machine comprising a suitable supporting frame; a second frame pivotally mounted upon the supporting frame; means for securing the second mentioned frame at various angles relatively to the mattress; roll forming means slidably mounted upon the frame to form a roll on the corners of a mattress or the like; roll retaining means; suitable sewing mechanism mounted within the frame to sew the 105
110
115
120
125

8. A mattress roll forming machine comprising a suitable table to support a mattress; a supporting frame slidably mounted at the edges of the table and arranged to traverse the entire periphery of said table; a second frame pivotally mounted upon the first mentioned frame; means for securing the second mentioned frame at various angles relatively to the table; a pair of roll forming fingers slidably mounted upon the second mentioned frame to engage surfaces of the mattress adjacent the corners thereof and to form a roll on said corners; suitable rolls to engage and retain the roll formed by the fingers; means for releasing the rolls from the mattress; a suitable sewing mechanism mounted within the second mentioned frame to sew the formed roll at its junction with the mattress and thereby permanently secure said roll; means for moving the machine at regular intervals along the edge of the table and around the corners thereof; driving means to operate the sewing mechanism; a suitable cam secured to the sewing mechanism driving means to operate the roll forming fingers when the sewing mechanism is withdrawn from the mattress and roll and to retain the engagement of said fingers with the mattress while the machine is moving forward and to release said fingers as soon as said forward movement is completed; and means for moving the roll forming fingers forward when released from the mattress. 55
- 10 15 20 25 30
9. A mattress roll forming machine comprising a suitable table to support a mattress; a supporting frame slidably mounted at the edges of the table and arranged to traverse the entire periphery of said table; a second frame pivotally mounted upon the first mentioned frame; means for securing the second mentioned frame at various angles relatively to the table; a pair of roll forming fingers slidably mounted upon the second mentioned frame to engage surfaces of the mattress adjacent the corners thereof and to form a roll on said corners; suitable rolls to engage and retain the roll formed by the fingers; means for releasing the rolls from the mattress; a suitable sewing mechanism mounted within the second mentioned frame to sew the formed roll, at its junction with the mattress and thereby permanently secure said roll; means for moving the machine at regular intervals along the edge of the table and around the corners thereof; driving means to operate the sewing mechanism; a suitable cam secured to the sewing mechanism driving means to operate the roll forming fingers when the sewing mechanism is withdrawn from the mattress and roll and to retain the engagement of said fingers with the mattress while the machine is moving forward and to release said fingers as soon as said forward movement is completed. 60
- 35 40 45 50 55 60 65
10. The combination with a mattress roll forming machine of a pair of fingers to enter the said mattress, gather the stuffing therein into a corner of the mattress and thereby form a roll on the said corner; means for sewing the formed roll; means for moving the sewing means forward toward the roll forming means while said roll forming means is in engaging relation with the mattress; and means for retaining the engaging relation of the roll forming means with the mattress while the sewing means is moving toward said roll forming means. 70
- 75 80
11. The combination with a mattress roll forming machine of a pair of fingers to enter said mattress, gather the stuffing therein into a corner of the mattress and thereby form a roll on the said corner; means for sewing the formed roll; means for moving the sewing means forward toward the roll forming means while said roll forming means is in engaging relation with the mattress; means for retaining the engaging relation of the roll forming means with the mattress while the sewing means is moving toward said roll forming means; and for releasing the roll forming means from the mattress and moving same forward at the completion of the forward movement of the sewing means. 85
